(57) CLAIM

I claim, the ornamental design for a water purification media device, as shown and described.

DESCRIPTION

FIG. 1 is a front top perspective view of a first embodiment of the design;

FIG. 2 is a front view of the embodiment of FIG. 1;

FIG. 3 is a rear view of the embodiment of FIG. 1;

FIG. 4 is a first side view of the embodiment of FIG. 1;

FIG. 5 is a second side view of the embodiment of FIG. 1;

FIG. 6 is a top view of the embodiment of FIG. 1;

FIG. 7 is a bottom view of the embodiment of FIG. 1;

FIG. 8 is a front top perspective view of a second embodiment of the design;

FIG. 9 is a front view of the embodiment of FIG. 8;

FIG. 10 is a rear view of the embodiment of FIG. 8;

FIG. 11 is a first side view of the embodiment of FIG. 8;

FIG. 12 is a second side view of the embodiment of FIG. 8;

FIG. 13 is a top view of the embodiment of FIG. 8;

FIG. 14 is a bottom view of the embodiment of FIG. 8;

FIG. 15 is a front top perspective view of a third embodiment of the design;

FIG. 16 is a front view of the embodiment of FIG. 15;

FIG. 17 is a rear view of the embodiment of FIG. 15

FIG. 18 is a first side view of the embodiment of FIG. 15;

FIG. 19 is a second side view of the embodiment of FIG. 15;

FIG. 20 is a top view of the embodiment of FIG. 15;

FIG. 21 is a bottom view of the embodiment of FIG. 15;

FIG. 22 is a front top perspective view of a fourth embodiment of the design;
